CLAIM

The ornamental design for a display screen or portion thereof with a graphical user interface of a mobile device, as shown and described.

DESCRIPTION

FIG. 1 is a front view of a first embodiment of a display screen with a graphical user interface of a mobile device. FIG. 2 is a front view of a second embodiment of a display screen with a graphical user interface of a mobile device. FIG. 3 is a front view of a third embodiment of a display screen with a graphical user interface of a mobile device; and,

FIG. 4 is a front view of a fourth embodiment of a display screen with a graphical user interface of a mobile device. The broken line illustrates the display screen or portion thereof and forms no part of the claimed design. The broken lines illustrate portions of the graphical user interface and form no part of the claimed design.
